(57) **CLAIM**

The ornamental design for a pressure cooker, as shown and described.

DESCRIPTION

FIG. 1 is a front elevational view of a pressure cooker showing my new design covered with a lid and with a colander received therein;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a cross-sectional view taken through line 7—7 of FIG. 1;

FIG. 8 is a front elevational view of the pressure cooker as shown in FIG. 1 covered with an alternative embodiment of lid and the colander removed;

FIG. 9 is a rear elevational view thereof;

FIG. 10 is a left side view thereof;

FIG. 11 is a right side view thereof;

FIG. 12 is a top plan view thereof;

FIG. 13 is a bottom plan view thereof;

FIG. 14 is a front elevation view of the colander received in the pressure cooker as shown in FIG. 1;

FIG. 15 is a rear elevational view thereof;

FIG. 16 is a left side view thereof;

FIG. 17 is a right side view thereof;

FIG. 18 is a top plan view thereof;

FIG. 19 is a bottom plan view thereof; and,

FIG. 20 is a cross-sectional view taken through line 20—20 of FIG. 18.
